UNITED STATES PATENT OFFICE.

WILLIAM DIETER, OF BROOKLYN, NEW YORK.

TORPEDO-FINDER.

1,319,051.

Specification of Letters Patent. Patented Oct. 21, 1919.

Application filed May 14, 1919. Serial No. 297,124.

To all whom it may concern:

Be it known that I, WILLIAM DIETER, a citizen of the United States of America, residing in Brooklyn, in the county of Kings, 5 city and State of New York, have invented certain new and useful Improvements in Torpedo-Finders, of which the following is a specification.

This invention provides a device for facilitating the finding of torpedoes after trial or practice runs.

In the testing of torpedoes and subsequently in naval practice, it is customary to launch them under conditions precisely duplicating those in actual warfare, except that a harmless practice head is used in place of the war head containing an explosive charge. In such practice runs the 10 torpedo often travels as far as eight miles, and under actual conditions of weather and water, it is frequently almost impossible to determine where in its course the run of the torpedo ends. Although the torpedo is designed to float to the surface at the end of 15 a practice run, yet it often happens that it fails to do so for one cause or another, usually because it may have buried itself so deeply in mud that it is unable to rise. So great is the difficulty of finding torpedoes 20 after such practice runs, that it happens that in a considerable percentage of cases the torpedo is never recovered, a circumstance involving very heavy loss.

Many efforts have been made to locate or 25 disclose the position of torpedoes at the end of a practice run. For example, the torpedo at the end of its run has discharged compressed air rising in bubbles to the surface; or it has discharged a gas such as calcium 30 phosphid, which on rising to the surface would take fire and emit smoke; or it has been caused to eject a float which would rise to the surface. The difficulty with all such schemes is that when the torpedo buries itself in mud, as it usually does when it fails 35 to float to the surface, any finder is apt to be unable to rise through the mud so as to reach the surface. The most successful means thus far used has been in the nature of a float or buoy towed behind the torpedo during its run, using a line of sufficient length so that however deeply the torpedo 40 may sink, the float may still reach the surface. This plan, however, involves practical

difficulties which heretofore have tended to 55 discourage its adoption.

The present invention provides an improved construction whereby a finder in the nature of a float or buoy may be successfully launched and be towed after the torpedo in 60 its run. The buoy is preferably made tubular and the towing line passes through it. The buoy is held in a chamber or extension connected with the launching tube, and the line is wound on a reel and passes through 65 the buoy, and is attached to the tail of the torpedo. As the torpedo is launched it drags the line after it, the line being unreeled and paying off through the buoy until it is all 70 run out, whereupon a button or enlargement on its end strikes the end of the buoy and carries the latter with it, thereby launching the buoy, which thereafter is towed behind the torpedo. The peculiar merit of the invention lies in the provision for preventing 75 any fouling of the line, a difficulty which heretofore has proved practically insurmountable with finders of this type.

The preferred construction embodying the invention is shown in the accompanying 80 drawings, wherein—

Figure 1 is a sectional view showing the rear or breech portion of the launching tube, with the tail portion of the torpedo lying within it, ready for launching. The view is 85 a longitudinal, vertical mid-section through the launching tube, the torpedo being partly broken away and shown in mid-section;

Fig. 2 is a vertical transverse section on the line 2—2 in Fig. 1; 90

Fig. 3 is a similar section on the line 3—3 in Fig. 1;

Fig. 4 is a fragmentary longitudinal section showing a portion of the torpedo to illustrate the connection of the towing line 95 therewith;

Fig. 5 is an elevation on a small scale, showing the torpedo in its run towing the buoy;

Fig. 6 shows the torpedo buried in mud at 100 the end of its run, and the buoy in action;

Fig. 7 is a vertical section showing a modification.

Referring to Fig. 1, A is the torpedo, B the buoy or float, C is the launching tube, 105 and D is the towing line.

The launching tube C has the usual breech-closing door E, with the usual cham-

bered projection F. To the rear of this projection is a tubular extension G which may conveniently be formed by screwing a piece of pipe centrally into the bore, so as to project aftwardly therefrom. The rear end of this tubular projection is partly closed by a cap H. The tubular portion G is of such size and shape as to form a close but free-fitting receptacle for the buoy. The buoy 5 is tapered at both ends, and the cap H has its opening small enough to engage the tapered rear end portion of the buoy, the latter preferably slightly projecting through it, as shown. The buoy is shown as made tubular, being bored through longitudinally, and the towing line D passes through this bore. The buoy may be of wood or of any material sufficiently light to insure its floating to the surface when the towing effort 10 ceases. The line D is coiled outside of the launching tube (instead of within it, as heretofore), so that when the torpedo is launched it may freely pay out through the bore in the buoy. To prevent possibility of 15 fouling, the preferable way is to coil the line on a reel J which is pivoted aft of the launching tube, so that its peripheral groove, in which the line is wound, is approximately tangential with the bore, so that the line 20 when winding from the reel may freely enter and pay out through the bore of the buoy. The reel may be conveniently mounted on a stationary spindle a, the head b of which is riveted or otherwise fixedly connected to a bracket arm c which is fastened to any convenient support, preferably the tubular portion G to which it may be 25 clamped by clamping means d and bolts e. To prevent the reel from overrunning and 30 paying out the line too fast, so that the line might foul, the reel is subjected to a slight tension, as by means of a washer f, spring g, and adjusting nut h (Fig. 2).
For attaching the line to the torpedo, the 35 preferable means is to provide a swivel connection with the inner propeller shaft K of the latter. This shaft is always made tubular and affords the discharge for the exhaust air from the engine or turbine. 40 Where it is locked to the forward section K' of the inner propeller shaft by means of the usual screw i, a swiveled bail L is conveniently connected. In the construction shown, this is done by means of a screw j entering 45 the head of the screw i and having a shoul- 50 dered neck portion confining the internal flange of a loose collar k to which the bail L is pivotally united. The parts K', i, j, being rotative, the parts k L may remain 55 stationary or nearly so. To the bail L is connected a wire D' which extends slightly aft of the torpedo and terminates in a swivel m to which is connected the line D proper. This double swivel construction effectually 60 guards against any undue tendency to twist 65

the line. The line is best made of a high grade of fishing line.

The aft end of the line D has attached to it an enlargement or button M sufficiently larger than the bore through the buoy so 70 that when the line is all paid out and this button strikes the buoy, it will push the latter ahead of it and launch the buoy out of the chamber formed by the tubular receptacle G. The stretch of the line as it tautens 75 makes this launching operation sufficiently moderate to avoid undue shock.

The characteristic feature of the present invention is the provision of the buoy with a bore or orifice through which the line 80 passes, so that upon launching the torpedo the line pays out through the buoy, or a part thereof, until the enlargement or button on its tail end strikes the buoy and carries the latter out from the launching tube. This 85 construction and arrangement avoids the difficulties heretofore experienced in the fouling and often breaking of the line, with the consequent failure of the buoy to follow the torpedo and serve as a finder when the 90 latter reaches the end of its run.

The line is made long enough so that at the end of the run of the torpedo, no matter how deeply it may bury itself in mud, there will still be sufficient free line to enable the 95 buoy to float to the surface. Such a buoy projecting like a beacon above the water, may be readily seen, even though quite small, and when once found it is a simple matter to locate the torpedo and to either immediately recover it or mark it for future recovery.

While the specific construction described is that deemed preferable, yet it is to be understood that the invention is not limited 105 to the precise details, proportions and arrangements set forth, but may be varied within reasonable limits according to requirements and as may be suggested from the standpoint of the skill or judgment of 110 the engineer. For example, it is not essential to the invention that the coiled reserve of line and the reel carrying it, be located externally to and aft of the launching tube, as they might, by reconstructing the breech 115 portion or door of the tube, be located within it to like effect, that is, so that the line as it pays off the reel may reave out through the buoy.

While it is preferable to make the buoy 120 tubular, yet a fair equivalent therefor would be found in the provision of a loop at the bow end of the buoy, through which loop the line may pay and be caught by a button or enlargement on the end of the line. This 125 is shown in Fig. 7, which illustrates the modifications here suggested, the reel J being located within the rear door E' of the launching tube, and the buoy B being non-tubular and having at its forward end a 130

wire *p* terminating in a loop *q*. This loop forms an orifice which is the equivalent of the orifice formed by the bore of the tubular buoy in the preferred construction first 5 described. In the present construction the rear cap *H'* is imperforate, a fact which renders it the preferable construction for underwater tubes. The construction first described is the preferable one for over-
10 water launching tubes.

The swivel construction for connecting the towing line to the torpedo has the advantages of affording a central and symmetrical connection, and preventing any fouling 15 of the line with the propeller screws. To gain these advantages it is necessary to make the connection with a revolving element of the torpedo, and this, to avoid undue twisting of the towing line, necessitates the use 20 of one or more swivels. The interposition of the wire section *D'* between the bail *L* and the swivel *m* protects the line *D* from any engagement with the torpedo which might result in chafing, and also protects it 25 from the heat of the exhaust gases, the swivel *m* being located far enough aft so that the water may close in at the wake of the torpedo and keep the line cool.

What I claim is:—

- 30 1. The combination with a torpedo of a torpedo finder comprising a buoy having an orifice, a line attached to the torpedo and run through such orifice of the buoy, the surplus line being coiled aft thereof, and the line terminating in an enlargement larger than said orifice, so that as the line is paid out, the end portion carries the buoy with it.
2. The combination with a torpedo of a finder according to claim 1, having a reel 40 on which the coiled line is wound, so that as the torpedo is launched, the line pays off the reel and through the orifice of the buoy.
3. The combination with a torpedo and launching tube, of a finder comprising a 45 buoy having an orifice, and a towing line attached to the torpedo and paying through such orifice, the launching tube having means for holding the buoy so that it is free to be drawn out when the line is taken up.
- 50 4. The combination of claim 3, the hold-

ing means on the launching tube consisting of a tubular portion forming an elongated chamber loosely fitting the buoy.

5. The combination of claim 3, the buoy being tubular, its holding chamber having 55 a rear opening, and the line passed through the bore of the buoy and said opening and coiled rearwardly of and exterior to the launching tube.

6. The combination with a torpedo of a 60 torpedo finder comprising a tubular buoy, a towing line attached to the torpedo and run through the bore of the buoy, and a button or enlargement at the aft end of said line adapted to abut the buoy to tow it after the 65 torpedo.

7. The combination with a torpedo of a torpedo finder comprising a tubular buoy, a towing line attached to the torpedo and run through the bore of the buoy, and a reel aft 70 of the buoy on which the line is coiled, so that when the torpedo is launched, the line pays off the reel and through the buoy.

8. The combination with a torpedo and launching tube, of a finder comprising a 75 buoy having an orifice and a towing line attached to the torpedo paying through such orifice, a reel on which the line is wound, and means for applying a tension to the reel to prevent overrunning. 80

9. The combination with a torpedo and launching tube, of a finder comprising a buoy and a towing line therefor, and means for attaching such line to the torpedo, including a swivel connection to a revolving 85 part at the tail of the torpedo.

10. The combination of claim 9, said swivel connection engaging the inner propeller shaft.

11. The combination of claim 9, said 90 swivel connection engaging the forward part of the inner propeller shaft.

12. The combination of claim 9, including a wire interposed between the swivel connection with the torpedo and the towing 95 line at a point aft of the torpedo.

In witness whereof I have hereunto signed my name.

WILLIAM DIETER.
